CLAIM

The ornamental design for compost pail, as shown and described.

DESCRIPTION

FIG. 1 is a front perspective view of a composite pail showing my new design;

FIG. 2 is a rear perspective view thereof;

FIG. 3 is a bottom rear perspective view thereof;

FIG. 4 is a front plan view thereof;

FIG. 5 is a right side elevational view thereof, a view taken from the left side being a mirror image;

FIG. 6 is a rear plan view thereof; and,

FIG. 7 is a partial section taken along lines 7—7 of FIG. 6.

*Fig. 1**Fig. 2**Fig. 3**Fig. 4**Fig. 5**Fig. 6**Fig. 7*
